UNITED STATES PATENT OFFICE.

HARRIS S. GREENO, OF ST. LOUIS, MISSOURI.

TRUSS.

SPECIFICATION forming part of Letters Patent No. 397,545, dated February 12, 1889.

Application filed November 5, 1888. Serial No. 289,973. (Model.)

To all whom it may concern:

Be it known that I, HARRIS S. GREENO, of St. Louis, Missouri, have made a new and useful Improvement in Trusses, of which the following is a full, clear, and exact description.

The improvement relates, mainly, to air-pad trusses; and it consists, partly, in the means for increasing the elasticity and accommodativeness of the pad, partly to the relative construction of the pad and its holder, and partly to the means for adapting the pad-holder and pad to any of the truss-springs and belts commonly in use, substantially as is hereinafter set forth and claimed, aided by the annexed drawings, making part of this specification, in which—

Figure 1 is a view in perspective of the pad-holder; Fig. 2, a view in perspective of the pad; Fig. 3, a section of the pad and holder on the line 3 3 of Fig. 4, which in turn is a section of the same parts in the line 4 4 of Fig. 3; and Fig. 5, a view in perspective of the improved pad and holder attached to a truss-spring.

25 The same letters of reference denote the same parts.

The air-pad already upon the market is objectionable by reason of its insufficient elasticity. That portion of the pad with which the pad-holder is immediately connected is so made and so united with the holder as virtually to be about as rigid as the holder itself. The connection with the holder is also such as to cause the pad to wear and break away at the point of connection, and the life of the pad in consequence to be prematurely terminated. These difficulties are largely, if not entirely, overcome and an improved truss obtained by means of the present construction.

40 A represents the pad. It is hollow, to be inflated with air, and is made of an elastic material—such as rubber—and that portion, a, of it which is turned toward the body of the patient, and which may be termed the “face”

45 of the pad, is of any of the customary shapes. The opposite portion or back, a', of the pad, on the other hand, differs materially from the corresponding portion of previously constructed air-pads. In place of being flat it is crowned, so that the central portion, a'', of the back projects more than its peripheral por-

tion. A shank, a'', projects from its central portion. The shank is preferably quite narrow in one direction, as shown in Fig. 3, and long in the opposite direction, as shown in Fig. 4, 55 and at or toward its outer end the shank is provided with a head, preferably in the form of the flange a''. The shank is preferably integral with the main portion of the pad, and is thus of elastic material. 60

B represents the pad-holder, which in practice is of metal. Its main portion b is a flat plate adapted to be pressed against the back of the pad. It is slotted at b' to enable the plate to be passed onto the shank. In thus attaching the plate advantage is taken of the yielding quality of the material of which the shank is composed, so that it is unnecessary to widen the slot b' to the width of the flange a'', and hence the principal portion of the slot 70 is only as wide as the neck of the shank; but at one of the ends the slot is widened, as at b'', to the width of the flange a''. The plate is attached by passing the widened portion of the slot onto the shank-flange and slipping 75 the plate endwise and downward upon the shank until the plate has been passed below the flange a'' and onto the neck of the shank, as shown in Fig. 3. The other parts of the pad-holder are a bridge, b'', which is attached 80 to the plate and extends over the pad-shank, a catch, b'', pivoted to the plate at b'', and thereby adapted to be turned around, as indicated by its two positions, (shown, respectively, in Figs. 1 and 5,) and notched at b'' to 85 enable the catch, when turned into the position of Fig. 5, to receive and grip the pad-shank and thereby secure the holder from slipping endwise upon the pad-shank, and a clamp-screw, b'', which engages in the bridge 90 and is used to attach the holder to the spring C or belt of the truss. The entire truss is not shown, as the unrepresented portion is unnecessary to an understanding of the improvement. The combination of the clamp-screw and the bridge b'', substantially as 95 shown, enables the improved holder and pad to be attached readily to any ordinary truss spring or belt. This I consider quite an advantage, as thereby the benefits of my improved pad and holder can be obtained in 100 conjunction with almost any variety of truss

which may be preferred by the patient. By reason of the convexity of its back the pad is rendered doubly elastic. In using it not only does its face, but the back also, of the pad yields elastically to pressure. The back yields until the holder-plate comes to a bearing upon the back, as represented in Fig. 4, and then the face of the pad can yield farther. As the holder-plate works toward and from the pad-back, no part of the pad is compressed or drawn in a way calculated to work an injury to the pad. Owing to the shape and flexibility of the pad-shank and the manner of connecting the holder therewith, the pad can in applying it be readily turned, so that its back is out of parallel with the holder-plate, or the back of the pad may be adjusted to be parallel with the holder-plate.

The above-described construction—namely, the combination of the air-pad, the pad-holder, and the clamp-screw—I have put upon the market as an article of merchandise to be sold to go with any of the ordinary truss springs or belts.

25 I claim—

1. The combination, substantially as described, of the air-pad and the pad-holder, said air-pad having the rubber shank a^3 , integral with the pad, and said pad-holder having the slotted plate b .

2. The combination, substantially as described, of the air-pad and the pad-holder, said air-pad having the shank a^3 and flange a^4 , and said pad-holder consisting of the plate b , slotted at $b' b^2$, the bridge b^3 , and the pivoted notched catch b^4 .

3. The combination, substantially as described, of the air-pad having the convex back and the shank having the flange, with the pad-holder composed of the plate b , slotted at $b' b^2$, the bridge b^3 , and the pivoted notched catch b^4 .

4. The combination of the air-pad having the convex back and the shank, the pad-holder having the slotted plate and the bridge, and the clamp-screw, said shank being of rubber and integral with said pad, substantially as described.

45 5. The combination of the air-pad having the convex back and the shank having a head, the pad-holder composed of the slotted plate, the bridge, and the pivoted notched catch, and the clamp-screw, substantially as described.

Witness my hand.

HARRIS S. GREENO.
